UNITED STATES PATENT OFFICE.

CHARLES D. WOOD AND EDWARD R. DE LONG, OF BOSTON, MASSACHUSETTS.

SAFETY DEVICE FOR ELEVATOR WELLS.

Application filed March 6, 1922. Serial No. 541,578.

To all whom it may concern:

Be it known that we, CHARLES D. Wood and EDWARD R. DE LONG, citizens of the United States, and residents of Boston, in the 5 county of Suffolk and State of Massachusetts, have invented certain new and useful Improvements in Safety Devices for Elevator Wells, of which the following is a specification.

10 This invention relates to the protection against injury from accidental falls in elevator wells and is intended to provide a simple device that is capable of easy and convenient application to various types 15 of elevators which shall protect passengers or others from injurious falls in case any person should accidentally step or fall through an open door in the well either when the car is above or below said floor.

20 In its essential features the invention comprises a series of flexible suspending elements hung from the upper part or top of the elevator well and extending downward to the top of the car when the car is at the bottom 25 of the well, to which flexible suspenders are connected at intervals a series of movable platforms or nets which nest on the top of the car as the car moves upward, but which are arranged to hang in succession 30 below the individual floors as the car descends. The same construction is applied underneath the car to protect that portion of the well below the car. With the construction and arrangement embodying the 35 principles of this invention it is possible, at slight expense, to protect against any fall that would be injurious or harmful since the safety platforms or nets may be spaced so as to lie practically level with or slightly 40 below each floor thereby preventing a fall for any distance that would be harmful or productive of injury.

In the accompanying drawings we have 45 illustrated the preferred construction and arrangement embodying the principles of this invention in which:

Figure 1 is a side elevation showing so much of an elevator well as may be necessary to understand the application of the 50 present invention, the car or elevator being shown at an intermediate position.

Figure 2 is a detail perspective view show-

ing a preferred construction of the safety platform or net.

Figures 3 and 4 are detail views of the 55 platform frame work.

Figure 5 is a larger scale view showing the connecting lacing for interconnecting the separate portion of the net or platform.

Fig. 6 is a fragmentary view partly in 60 elevation and partly in section showing a means of connecting the safety platforms to the chains by which they are suspended.

Fig. 7 is a plan view on a relatively enlarged scale of a net-receiving tray em- 65 ployed with the invention; and

Fig. 8 is a transverse vertical sectional view of such tray.

The drawings show the well-known construction of elevator well 1, extending 70 through the different floors 2, of the building in which is suspended or supported the movable car or elevator 3, to which access is had through the usual doors 4 on the different floors. The suspension or counter-weight 75 cables 5, are located in their usual position and it will be understood that the device is equally applicable to a cable-suspended or to a plunger-supported elevator.

In the top of the well we provide suitable 80 anchorage members 7, comprising eye-bolts or other suitable means for supporting a plurality of flexible suspension members 8 which are preferably in the form of chains, and are preferably located at each of the 85 four corners of the well. The flexible suspension elements hang from the fixed anchorage elements 7 so as to extend to the top of the car 3 when the car is at the bottom of the well. At suitable intervals, preferably 90 corresponding to the distance between successive floors, we connect to the suspending elements a series of movable platforms 9 which are preferably in the form of a net work having special features which readily 95 adapt it to be applied to either the plunger or the cable type of elevator.

On the top of the car is disposed a tray 6 whose peripheral walls extend somewhat beyond the planes of the vertical suspension 100 chains 8, so that as the car ascends from the bottom of the well the different nets above it successively nest in the tray or receptacle so that when the car reaches the top

of the well all the overhead nets nest on the top of the car. On the other hand, as the car descends, the individual nets in succession are left suspended at or below the 5 different floor-levels until the car reaches the bottom. Obviously, no injurious fall can result from walking through any open doorway in the elevator well since immediately beneath the floor, or practically at the level 10 thereof, is placed a platform to catch any person or body passing through any door.

A similar series of platforms or nets are suspended from the bottom of the car to the bottom of the well by means of similar 15 suspenders 14 connected to eye-bolts or other anchorage members 12, and carrying a similar series of movable platforms 9 which are distributed along the well beneath the car as the car rises, and nest in the bottom 20 part of the well when the car descends.

In either case, the flexibility of the suspension elements 8 and 14 permit them to coil or fall on their supporting platform either 25 on the car or near the bottom of the well in position to allow them to straighten out as the car moves up and down.

The individual platforms may be of any suitable construction, but they are herein 30 shown as comprising a peripheral frame 9^a comprised of metal tubing which is interrupted or severed at one point to receive a connecting turn buckle 9^b which may be entirely removed so as to facilitate the application 35 of each platform around the suspension cable or the plunger as the case may be which, of course, will be at the middle of the car. The interior space enclosed by the peripheral frame 9^a is preferably closed by a suitable net work 9^c which, 40 however, is formed to leave an open space in the center with a path leading from the center to the space in the frame closed by the turn buckle 9^b. We may also provide at 45 each corner a thin plate 9^d to receive the coiled suspension chains to guard against entanglement with the net. Each platform is flexibly connected by short connecting members 10 with the vertical suspension 50 members. The plates 9^d also act as separating members to keep separate the lengths of the suspension chains immediately above and below each platform so that they are not likely to become entangled with each 55 other.

For convenience the peripheral wall 6^a of the net-receiving tray is hinged as at 6^b to open apart to permit its application around the elevator cables, and the peripheral wall sections are provided with inwardly projecting lugs or ledges 6^b on which are located the two false bottom sections 6^c.

It will be readily perceived that complete provision is made for quickly and cheaply 60 applying this device to different types of

elevators and requires no alteration whatever in the construction of the building or of the elevator, involving as it does merely the provision of suitable anchorage members for the platform and suspenders applied, respectively, to the top and bottom of the well and to the top and bottom of the car.

After the different nets have been placed in position around the central cables the turn 75 buckle 9^b is applied to the threaded nipples 90 to connect firmly the severed ends of the frame 9^a and a lacing 9^e or other convenient connecting means is applied to connect together the severed edges of the net through 80 which the cables pass in assembling the device.

The short flexible suspension members or chains 10, connecting each individual platform with the suspension chains 8 are used 85 to facilitate the proper coiling of the suspension chains when the different nets are being nested above or below the car. The short suspension members not only do not interfere with the flexibility of the main 90 suspension chain, but their weight on the chain, when the net is being nested on the top of the car or on the bottom of the well, tends to draw inwardly the main suspension chains so that they will coil over the receiving corner plates 9^d.

What we claim is:

1. The combination with an elevator well and elevator operable therein, of a safety device comprising a protective platform, a plurality of flexible suspension elements by which said platform may be suspended, said platform consisting in a rigid peripheral frame, and an interior supporting network, said frame and said network constructed to provide an opening from the periphery of the platform to the center thereof to permit the fitting of the platform around the supporting element of the elevator, and means for bridging said frame and said network at the locality of said opening after the platform has been placed in position for use in the elevator well.

2. A safety device for elevator wells comprising a series of spaced apart suspension members, a protective platform engaged therewith consisting in a tubular peripheral frame, and an interior network held thereby, said frame and network being severed to provide an opening from the periphery of the platform to the center thereof to receive the supporting element of the elevator,

a turn buckle for bringing the severed portion of the frame to render the same rigid, and means for closing the severed portion of said network after the insertion of the elevator supporting element.

3. An elevator safety device, embracing in combination a series of flexible suspension chains suspended in the elevator well

each being connected with the car at one end, a series of safety platforms and a series of short suspension chains connecting the corner portion of said platform with the main suspension chains inwardly of the main suspension chains, whereby the weight of said suspension chains, when the platforms are being nested upon each other, tends to draw inwardly the main suspension chains and cause them to coil above 10 the respective platforms.

In witness whereof, we have subscribed the above specification.

CHARLES D. WOOD.
EDWARD R. DE LONG.
